STACKING INSERT FOR CONTAINERS

Hans Ake Hilding Skagmo, Helsingborg, Sweden, assignor
to Svenska Elopak, Helsingborg, Sweden

Continuation-in-part of design application Ser. No.
216,324, Jan. 7, 1972. This application July 19,
1973, Ser. No. 380,828

Term of patent 14 years

Int. Cl. D9—99

U.S. Cl. D9—294

FIG. 1

FIG. 2

FIG. 3

FIG. 4

FIG. 5

FIG. 1 is a top perspective view of a stacking insert for containers embodying my new design.

FIG. 2 is a top view thereof.

FIG. 3 is a bottom view thereof.

FIG. 4 is a side view thereof.

FIG. 5 is an elevational view looking from the left of FIG. 4.

This application is a continuation-in-part of my co-pending application Ser. No. D. 216,324 filed Jan. 7, 1972.

I claim:

The ornamental design for a stacking insert for containers, substantially as shown and described.
